HAND STAMPS

Carl E. Carlsen, 867 3rd Ave., New York, N.Y.
Filed Mar. 29, 1963, Ser. No. 269,025
4 Claims. (Cl. 101—125)

This invention is a continuation, in part, of the applications for patents, Ser. Nos. 72,667 and 223,293, filed respectively Nov. 30, 1960 (and allowed) and Sept. 10, 1962, now U.S. Patents 3,101,048 and 3,103,879, and constitute in combination with the features disclosed in the latter and the new features added herein, a further improvement in hand stamps, as will be set forth herein-after.

In the present invention, a hand stamp comprises two parts, which may easily be locked together; a feature especially suitable in small stamps, because it will expose one part, that is the printing cylinder, to be completely re-inked from the inside thereof, without removing the stencil.

Furthermore this construction facilitates the easy cleaning of the device, as each part may be cleaned separately with no interference by any attached parts; a feature most desirable in a small stamp.

Another advantage of this construction is that the actual printing curve of the device is herein more flat than those commonly used, whereby the necessary rolling of the stamp would be shorter, and the pressure applied to the ink-storage pad would be more direct and effective; at the same time a more nearly flat curvature, incidental to this construction, would have the tendency to reduce the needed pressure on the storage pad, and consequently a stamp with a more nearly flat curvature would be easier to operate.

In the drawing, where similar characters of reference indicate corresponding parts:

FIGURE 1 is an exploded view showing two parts comprising my stamp device.

FIGURE 2 is a top plan view of the inside of the bottom part of my said device.

FIGURE 2a is a detail view, showing a member adapted to apply pull to a stencil.

FIGURE 3 is a perspective view of my device assembled.

FIGURE 4 is an enlarged transverse sectional view taken on the line 4—4 in FIGURE 3.

FIGURE 5 shows a box adapted to enclose a hand stamp, with accessories; and having the top or lid of said box made as a printing base, as shown in section in said figure.

Referring more particularly to the drawing, the numeral 10 indicates the upper part of my stamp device, having attached thereto a handle 11.

The said upper part is formed with an extended projection 12 adapted to be received by a slot 13 in the lower part 14 of said stamp device.

An ink absorbing storage pad 15 is permanently secured underneath the upper part 10, as shown in FIGURE 1 in dotted lines, and in FIGURE 4.

The lower part 14 of the stamp device shown in FIGURE 1 is a printing cylinder formed with perforations 16.

The said printing cylinder 14 is at each end formed with cut-away portions 17, 17 to permit a printing pad 18 to extend beyond said printing cylinder and thereby prevent the latter from touching the stencil 19.

The said printing cylinder has in one of its sides a small depression 20, which forms a means for locking the parts 10 and 14 together, after the extended projection 12 has been made to engage the slot 13.

The printing cylinder 14 is further formed with prongs 22, 22 adapted to engage the slots 25, 25 for securing the stencil 19 to the printing cylinder 14; said stencil is

2

wrapped around the outer surface of the part 14 and kept under stress by means of a flexible member 23 attached to a metal strip 24.

The reenforcing papers 26, 26 are, as shown at 27, 5 reversely bent thereby forming an opening 29 adapted to receive said metal strip 24 with the flexible part 23 which is stressed over the extended part 21, thereby applying a pull to the stencil.

In order to lock the two parts flexibly together the 10 extended part 12 is inserted in the slot 13 on the starting side of the device; the upper edge of said slot serves the purpose of locking, and the slot is made so large that it will permit part 12 to move freely downwardly and thus permit part 10 to press upon the storage pad 15. A 15 similar locking feature is applied to the front side of the stamp where the edge of part 10 is forced below the depressed part 20 by which it is locked, leaving at the same time said part 10 free to press farther down upon the storage felt.

20 In order to open the lock, place one hand on the edge of the springy U-shaped printing cylinder 14, while applying a rearward pressure upon the handle with the other hand.

In applying the ink, the storage pad 15 is saturated with 25 ink and the two parts are locked together, while some ink is applied to the printing pad, and the stencil attached.

In order to apply fresh ink, the stamp is opened into its 30 two parts without disturbing the stencil, and the ink is applied to the inside of the fully exposed printing cylinder 14. When the two parts are locked together the upper part 10 is free to press upon storage pad 15 which is larger than the actual printing space in 19a, but not as large as the printing cylinder 14, leaving an empty space 28, 28.

As the ink storage pad 15 is squeezed due to pressure on 35 the handle, the ink is forced through the perforations 16 and into the printing pad 18 which is inking the stencil 19. As the stamp is being used, the surplus ink in the printing pad 18 which has escaped the actual printing space 19a will, due to the outside pressure, return into the 40 empty space 28, 28 and into the storage pad 15 to continue its circulation, and in this way the stamp will distribute a small amount of ink for an even printing, and at the same time add to the cleanliness of the stamp.

The stamp is used in a rolling motion and started on 45 the side where the stencil is firmly attached to prongs 22, 22. The stencil having been prepared, on the typewriter or by means of a stylus for handwriting, now has the backing sheet torn away in the usual manner (not shown).

The stencil is reenforced at both ends with papers 26, 26 50 and close to the actual printing space 19a to prevent wear and tear of the stencil and to prevent smudging of the paper which is being printed, as the stamp is started and removed from said paper.

The reenforcing paper is turned reversely at one end to 55 form a loop 27; a separate part 24 is inserted in the latter whereby to apply a pull upon the stencil, as formerly explained.

What I claim as my invention, and desire to secure by Letters Patent of the United States, is:

60 1. A hand stamp having a handle and comprising an upper and a lower part or printing cylinder, said upper part being provided with a front edge and a rear edge, an extended projection disposed on said rear edge of said upper part adapted to be received by a slot in the printing cylinder, said slot being provided in the side of the printing cylinder and being of a size large enough to permit the upper part to move freely downwardly, said printing cylinder having a small depression whereby said extended projection engages the slot in said printing cylinder 65 and the front edge of said upper part is forced below said depression thereby locking said upper and lower parts to- 70

gether, an ink absorbing storage pad disposed between said upper and lower parts and subjected to pressure by said upper and lower parts, said printing cylinder being provided with perforations, said printing cylinder being at each end formed with cut-away portions, a printing pad 5 extending beyond said printing cylinder, prongs formed upon the latter and a stencil provided with slots engaged by said prongs, said stencil being wrapped around the outer surface of said printing cylinder, and means for keeping said stencil under stress.

2. In a device as claimed in claim 1 wherein two empty spaces are formed between the upper and lower parts adjacent said ink storage pad thereby holding excess ink from said pad.

3. In a device as claimed in claim 1 wherein both ends of the stencil are fastened to the printing cylinder.

4. In a device as claimed in claim 3 wherein the printing cylinder may be re-inked from the inside thereof without removing the stencil.
